US00D583658S

(12) **United States Design Patent**
Follansbee et al.

(10) **Patent No.:** **US D583,658 S**
(45) **Date of Patent:** **** Dec. 30, 2008**

(54) **CONTAINER COVER**

(75) Inventors: **Scott W. Follansbee**, Round Lake Beach, IL (US); **Frank A. Petlak**, Antioch, IL (US)

(73) Assignee: **Pactiv Corporation**, Lake Forest, IL (US)

(**) Term: **14 Years**

(21) Appl. No.: **29/293,543**

(22) Filed: **Nov. 30, 2007**

(51) **LOC (8) Cl.** **09-03**

(52) **U.S. Cl.** **D9/425**

(58) **Field of Classification Search** D9/414-418, D9/420-426, 430-432, 761, 737, 757; D7/357-360, D7/629, 602, 412, 542, 553.1-553.8, 538, D7/543-545, 557, 564-565, 584-587, 591, D7/615; 206/315.9, 467, 485, 521.1, 539, 206/564, 541, 546, 588, 766, 779; 220/23.8, 220/23.83, 281, 326, 367, 523, 556, 574, 220/675, 4.21, 4.23, 782, 835, 839; 229/406, 229/902-904, 906, 407, 110; D6/470, 397, D6/441

(57) **CLAIM**

The ornamental design for a container cover, as shown and described.

DESCRIPTION

FIG. 1 is a front view of a container cover.

FIG. 2 is a back view of the container cover, which is opposite of the front view of FIG. 1.

FIG. 3 is a first side view of the container cover.

FIG. 4 is a second side view of the container cover, which is opposite of the first side view of FIG. 3.

FIG. 5 is a top plan view of the container cover.

FIG. 6 is a bottom plan view of the container cover; and,

FIG. 7 is a perspective view of the container cover.

The portions of the drawings shown in broken lines represent environmental structure and form no part of the claimed design.

1 Claim, 5 Drawing Sheets
